United States Patent Office.

WEBSTER M. CLAYTON, OF NEW YORK, N. Y.

Letters Patent No. 100,858, dated March 15, 1870.

IMPROVEMENT IN STAIR-RODS.

The Schedule referred to in these Letters Patent and making part of the same

I, WEBSTER M. CLAYTON, of New York, in the county of New York, and State of New York, have invented certain Improvements in Stair-Rods, of which the following is a specification.

My invention relates to that class of devices for attaching a carpet to a stairs known as stair-rods; and

It consists of an ordinary concavo-convex bar provided with slides which are partly concavo-convex and partly rectangular. Said slides embracing the concavo-convex rod, and carrying serrated dogs, which, on forcing a screw through the slide and rod, expands the serrated dogs, forcing them into the tread and rise of the stairs, and firmly securing the carpet, (placed between the rod and the stairs,) to the stairs, as I will further explain by reference to the drawings, of which—

Figure 1 is a front view of my improved stair-rod;

Figure 2, a view of the opposite side;

Figure 3, a sectional view (on an enlarged scale,) showing the application of my invention to the tread and rise of a stairs;

Figure 4, an edge view of the slide; and

Figure 5, an edge view of the serrated dogs.

In the said drawings—

A indicates the concavo-convex stair-rod, provided with circular holes B B for reception of bracing-screws C C.

D D are the slides which embrace the stair-rod and fitting the convex surface of the rod, project inward into the angle formed by the tread and rise of the stairs, forming a support for the rod. (See fig. 3.)

These slides receive and carry the expansive serrated dogs E E. Said dogs being united by hinges f f, both slides and dogs are provided with circular holes for reception of the bracing-screws C C.

To attach a stair-carpet to a stairs, I place the end of the carpet at the first step, under the hall carpet, and I nail both down. I next partially strain the carpet over the steps, and I now place the stair-rod over the carpet in the angle formed by the tread of the first step and riser of the second, and I turn the bracing-screws C C forward, when the screws will bear against the serrated expansive dogs E E, forcing their serrated ends C into the tread and rise of the stairs, straining the carpet to the desired tension, and firmly attaching the carpet to the stairs, this operation being but the work of a moment; while to detach the stair-rod from the stairs, I merely reverse or draw the screws a little backward, when the serrated dogs will lose their hold on the steps, and the rod can be removed from the stairs.

What I claim is—

The slides D D, rod A, screws C C, and expansive serrated dogs E E, combined, arranged, and operating substantially as and for the purposes described and set forth.

In testimony whereof I hereunto set my signature this 12th day of February, 1870.

WEBSTER M. CLAYTON.
